MEANS FOR THE MANUFACTURE AND
REFINING OF PULP

William P. Gruendler, University City, Mo., assignor of one-fifth to Charles D. Altick, Dayton, Ohio, and one-fifth to Lloyd D. Smiley, Jackson Heights, N. Y.

Application September 7, 1937, Serial No. 162,670

2 Claims. (Cl. 92—26)

This invention relates to certain new and useful improvement in means for the manufacture and refining of pulp such as used in preparation of paper, board, felt, and made from rag and straw, wood chips or any suitable fibrous or vegetable stock.

Heretofore such pulp has been made by physical contact of wood against grindstones, rotary cutters, beaters, cone, disc and other similar devices. Even when the grain of said stock is disposed more or less parallel to the cutting or grinding action, the fibres of said stock are more or less damaged in their original length, and the paper made from said pulp is correspondingly weakened in strength.

By my process and the means whereby I carry it out, substantially all of this damage to the fibres is avoided, since it consists in the use of a liquid such as water, projected at a high velocity against the fibrous stock so as to produce a bursting or explosive effect upon the stock.

I prefer to obtain this high velocity by the centrifugal action of a rotor having cup-shaped pockets or other suitable vanes which deliver liquid and fibrous stock substantially radially at a high peripheral speed of 18,000 feet or more per minute.

For example: a rotor of 18 inch diameter operating at 3800 R. P. M. will give substantially 30 18,000 feet per minute peripheral speed. Likewise a rotor of 40 inch diameter at 1800 R. P. M. will give somewhat more than 18,000 feet per minute peripheral speed.

When working with fibrous stock and water under high pressure great centrifugal force is developed.

I have found in practical operation of my process with means similar to such hereinafter described, that the fibres produced from suitable fibrous stock are not damaged to any appreciable extent—only resinous and ligneous matter having been released and separated, leaving only the fibres at original or full length, which result has long been desired; and provides the means of working with much rawer pulp, which produces the following effects A, obtaining a high tensile increase per H. P. hour; B, high Mullen increase per H. P. hr.; C, less tear drop per point Mullen developed; D, good formation at high freeness; E, little freeness drop per point Mullen developed; and F porosity and bulk can be greater per same weight sheet, and are the essential features commonly known in paper making and highly desired.

In the accompanying drawing in which like

reference numerals indicate corresponding parts,

Fig. 1 represents a sectional elevation of a rotor A mounted in its casing for the primary defibration of the fibres, and connected in series with a similar rotor C through an interposed stock chest B;

Fig. 1a, a detail plan view of the curved throat;

Fig. 1b, a sectional detail of the rotor shaft packing;

Fig. 2, an end view of such a rotor in its casing and direct connected through a flexible coupling to a motor;

Fig. 3, a detail front view of the preferred form of cup-shaped vane as carried by said rotors; and

Fig. 4, a vertical central section of the same. 15

The preferred form of cup-shaped vane is shown in Figs. 3 and 4 and comprises a pocket P formed by a curved back 1 having a forwardly curved outer lip 5 and connected by comparatively thin sides 2. The lower portion is solid and 20 has a hole 3 through which passes a supporting rod. This rod acts as a pivot in emergency, but in practice the high centrifugal force fixes the vane in position as no wear is apparent in use. The adjacent inner wall portion of said pocket 25 is curved down around and then radially outward from said pocket to a discharge edge 4 as shown in Fig. 4, leaving the opening of the cup from the edge 4 to the outer lip 5 to form an inlet into the cup for the liquid vehicle of the 30 fibrous stock, and an outlet from the cup when discharged from said opening and thrown off said edge 4 by the centrifugal force developed by the rotation of said rotor.

The outer lip 5 is located further out from the 35 shaft 7 which is the center of rotation, than the edge 4. Also the forward curvature of the outer portion of the back wall adjacent this outer lip 5, tends to slice from the entering feed a portion of the mixture which then slides inward on the 40 curved back wall until it reaches the rounded bottom end of the pocket and is reversed in its direction when it is discharged over the shorter edge 4. The high velocity given to this portion of the mixture by the vane, due to the high 45 peripheral velocity of the cup-shaped vanes and the centrifugal force to which the mixture is subjected, causes the mixture to leave the discharge edge 4 with great force in substantially radial direction outward from the cup. This action is the 50 reverse of that of a turbine in which the force of the water is transmitted to the blades of the turbine, that is to say, in my process a high turbulent action is obtained and an immediate bursting effect is had, thereby causing the fibres 55

to be separated instantaneously from ligneous and resinous matter, and defibration to continue till the fibres are suitably refined for the desired use.

5 This vane may be of any other suitable form, and is supported by spaced disc plates 6 mounted on a rotor shaft 7 which is direct connected through a flexible coupling to a motor 8, Fig. 2, or otherwise. A casing 9 has a hopper throat 10 forming an inlet, and an inner cage 11 cooperating with said vanes. One wall face of this hopper inlet is formed by a hopper cross bar that is curved downward in said hopper and forward in the direction of rotation of the rotor, and is 15 also curved laterally backward to form a center ridge 10 (Fig. 1a), to spread the entering feed across the rotor like a double plowshare. The axial length of the vane or series of them, is substantially that of the throat inlet so that substantially all the feed passes into the cup-shaped vanes.

This cage is provided with radial faces 12, and alternating inclined faces 13 respectively connecting said radial faces, so that the mixture 25 of fibrous stock and its liquid vehicle entering by the hopper inlet of the machine A, is deflected inward again toward the rotating vanes in successive cascade form, after the same has been projected outward from the vanes at said high 30 velocity by said vanes of the rotor.

As shown by the drawing, there is such a space between the edges 5 of the vanes that the stock is not subject to any grinding action but only to the impact of liquid moving at high velocity as 35 stated, and therefore substantially the original length of fibres is maintained without any grinding disintegration—only a separation of the fibres from the ligneous or other portions of the stock that originally binds the fibres in their original 40 position therein. Also the radial and inclined faces 12—13 respectively having the curved connecting surface 12' as shown in Fig. 1, allow the said mixture to glide along the radial faces 12 and the inclined faces 13 and be reversed by the 45 curved faces connecting the radial and inclined faces and form a cascade having approximately the original velocity given it by the high rotating speed of the cup-shaped vanes, although being somewhat diminished by the frictional contact of 50 the mixture passing over the said surfaces. The mixture returned in cascade form is again intercepted by the cup-shaped vanes, increased in velocity, and again thrown centrifugally from the vanes at restored high velocity of substantially 55 18,000 ft. per min. (300 ft. per second), or more. It thus meets the mixture returning from the cage in reverse direction and only somewhat diminished in velocity. The resulting liquid vehicle impact of currents colliding from substantially 60 opposite directions, provides a greatly increased liquid force that acts with corresponding effect upon the fibres in the mixture, and produces a corresponding increase of efficiency in the resulting separation of the fibres from ligneous and resinous matter.

This primary defibration of the fibres in the machine A, is transmitted by a pipe 14 to a stock chest B having an agitator therein by which the mass of fibres is kept in suspension in the liquid vehicle which may receive additional liquid 70 to make the mixture of proper consistency before passing out of said stock chest into the inlet of the machine C.

In this second machine the fibres are subjected to the same high centrifugal action as in the ma-

chine A, but this refining machine is preferably provided with means to retard the outflow of the refined mixture till the fibres are of the required separation and refinement for the paper or other product for which the pulp is to be used.

This retarding means consists of a vertical partition or dam 15 in one end of a chamber in the casing below the cage, and is, preferably in several widths so that the height of its top may be adjusted as desired. The outflow of the product refined in said machine C through an opening dividing its cage and forming a free outlet 16 is thus regulated by said partition, so that the refined product is more or less retained in the cage and is backed up through said outlet for further 15 operation according to the height of said dam 15. An inclined bottom trough 17 directs the mixture to the dam and the discharge pipe 18.

A valve 19 toward the front of the casing and at the opposite end of the chamber from the 20 dam 15 of this machine C, will admit additional water below the cage when required to maintain the desired consistency and to regulate the outward flow down said inclined bottom 17 and over the dam to the discharge pipe 18.

The turbulent and high velocity action of the liquid vehicle in the casing of these defibrating machines produces internal liquid pressure, tending to cause leakage where the rotor shaft enters the casing. To avoid such leakage and maintain 30 internal pressure, I provide a stuffing box 20 of annular V-shape having a felt ring 21, of V-shape or otherwise, one leg of which closely encircles the shaft and the other leg is adjustably held against the side of the casing by the correspond- 35 ing face of the box 20, as indicated in Fig. 1b.

On account of the variations of hardness of different fibrous stock from which the fibres are obtained by defibration, a multiple number of such machines such as above described can be 40 used in carrying out my process. I have shown and described two machines with interposed stock chests for maintaining the proper consistency of the water or other liquid and the fibres undergoing defibration. Also it is understood that 45 suitable chemicals commonly used in digesters of pulp may be used as may be required for assisting in defibrating the fibres from the resinous and ligneous matter in the fibrous stock used.

Having thus fully described the process to which I subject the fibrous stock, I summarize the steps comprised in said process as follows:

Step a comprises subjecting fibrous stock to the impact of intercepted portions of liquid projected at high velocity.

Step b comprises projecting such liquid portions centrifugally at high velocity ranging from substantially 18,000 ft. or more per minute.

Step c comprises deflecting portions of the 60 mixture of fibers and vehicle liquid reversely at high velocity.

Step d comprises creating successively a cascade of said mixture against successive centrifugally projected portions of mixed fibers and 65 liquid.

Step e comprises projecting said portions of mixed fibers and liquid at a velocity substantially 18,000 ft. or more per minute for refining said fibers.

Step f comprises retarding the outflow of mixed fibers and vehicle liquid, lowering its consistency, again subjecting it to steps b, c, d and e for final refining, and discharging the refined product.

I claim:

1. A defibrating machine, comprising a casing having a cage, and a rotor mounted for driving liquid material through the cage, the inner wall of said cage having a plurality of diverging faces joined together by a cylindrical concave portion, one of said faces extending approximately radially of the cage and the other face being disposed at an obtuse angle to the first mentioned face, said rotor having pockets thereon, each of which has a forwardly curved outer lip and a radially extending edge connected by a curved intermediate portion to said lip, and means for controlling the outflow of liquid material from the cage. 5
2. A defibrating machine, comprising a casing having a cage, a rotor mounted for driving
